UNITED STATES PATENT OFFICE.

GEORGE MOSS, OF ST. PETER, MINNESOTA.

CLOTH.

No. 882,832.

Specification of Letters Patent. Patented March 24, 1908.

Application filed March 27, 1907. Serial No. 364,845.

To all whom it may concern:

Be it known that I, GEORGE MOSS, a citizen of the United States, residing at St. Peter, in the county of Nicollet and State of Minnesota, have invented a new and useful Cloth, of which the following is a specification.

The present invention relates to cloth for employment in chest protectors, under-clothing and like articles to be worn next to the skin.

It is well known that animal fiber, particularly the wool of lambs and sheep contains a grease or fat which is beneficial to the human system, and the primary object of the present invention is to produce as an article of manufacture, a cloth of a novel character, wherein the wool or other animal fiber constitutes the facing thereof, this fiber having the natural wool grease or animal fat still incorporated therein, and being soft and pliable, so that it can be worn against the skin, and while imparting its medicinal properties, will not chafe or otherwise injuriously affect the wearer.

25 The preferred embodiment of the invention is illustrated in the accompanying drawings, wherein:—

Figure 1 is a rear view of a piece of cloth constructed in accordance with the present invention. Fig. 2 is a face view of the same. Fig. 3 is a sectional view therethrough.

Similar reference numerals designate corresponding parts in all the figures of the drawings.

35 In the embodiment illustrated, the cloth consists of a backing 4 of open mesh woven fabric, and a facing 5 comprising a sheet or bat of thoroughly intermingled fiber having the natural animal fat or grease therein. This 40 facing is laid flat against the backing, as will be clear by reference to Fig. 3. Intersecting lines 6 of stitching are passed through and through both the facing and backing, and secure the sheet or bat of fiber to and flat 45 against the woven fabric backing. These lines of stitching thus serve to hold the parts together, leaving the intermingled fiber exposed so that it will come into contact with the skin and impart the medicinal proper-

ties of the grease contained therein to the 50 body. The said lines of stitching are close enough together so that the cloth may be cut in any direction, and the fiber will still be effectively retained to the edge of the cut. Moreover it will be evident that by having 55 the facing in a flat layer against the backing, the two parts will pass readily through a sewing machine not only when said parts are secured together, but when the cloth is made up into garments.

60 From the foregoing, it is thought that the construction, operation, and many advantages of the herein described invention, will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

65 As an article of manufacture, a cloth having medicinal properties and consisting of a 70 backing of open mesh woven fabric, a facing comprising a sheet or bat of thoroughly intermingled wool having the natural animal fat retained therein and spread out in a flat layer against one side of the backing, in order to 75 permit both to be passed through a sewing machine and intersecting lines of stitching 80 passing through both the facing and backing and securing the sheet or bat of fiber to and against the woven fabric, leaving the outer 85 face of the sheet or bat substantially flat and exposed so as to come in direct contact with the skin of the wearer, said sheet or bat lying flat against the backing between the lines of stitching and covering the open meshes in 90 the fabric.

In testimony, that I claim the foregoing as my own, I have hereto affixed my signature in the presence of two witnesses.

GEORGE MOSS.
